UNITED STATES PATENT OFFICE.

FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC SWITCHING MECHANISM.

1,252,462.

Specification of Letters Patent.

Patented Jan. 8, 1918.

Application filed August 16, 1916. Serial No. 115,178.

To all whom it may concern:

Be it known that I, FRANK A. LUNDQUIST, a citizen of the United States, residing at New York, in the county of New York and State of New York, have invented certain new and useful Improvements in Automatic Switching Mechanism, of which the following is a full, clear, concise, and exact description.

10 This invention relates to automatic switches of the panel type, and has for its objects certain improvements in the structure and operation of a switch of this type, whereby units of large capacity and with 15 the minimum number of operating parts may be conveniently constructed and operated.

One of the features of this invention relates to the construction of the switch, 20 whereby the contacts constituting one bank of terminals may be spaced twice as far apart as in the switches of this type previously constructed, without increasing the distance over which the contacting brushes 25 have to move between the first and last contact. In accordance with this feature of the invention, the terminals constituting a bank are mounted in parallel rows with the terminals of one row staggered with 30 respect to the terminals of another row, and brushes are provided which are adapted to travel freely between the rows of terminals without engagement therewith, but which may be swung in either direction into engagement with selected ones of said terminals.

According to another feature of this invention, the movement of a set of brushes to a selected contact bank is under control 40 of a single magnet which also controls the release of the brush carriage to bring it into operation. In accordance with this feature, there is provided a rotatable and vertically movable shaft adapted in one position to release a selected brush carriage, and in succeeding rotated positions, dependent upon the number of banks to which the brush carriage is common, to select the bank containing the terminals with which the 45 brushes are to connect. After the selection of the bank by the rotation of the shaft, it is moved vertically step by step to bring the brushes into position to engage the selected terminals in the bank. The movement of 50 the brush carriage in selecting a terminal

bank will be in steps of a length equal to the width of a bank, while the steps for bringing the brushes into position to engage the terminals in the bank will be in steps equal to the vertical distance between terminals of adjacent rows.

Other features of the invention relate to the provision and mounting of test terminals and coöperating brushes and other details looking to the simplification of the structure and operation of the switch.

In the drawings, Figure 1 is a diagrammatic view of circuits and mechanism of a switch embodying the features of this invention; Fig. 2 is a fragmentary view of the device shown in Fig. 1 and illustrating an alternative scheme for swinging the brush carriage into engagement with a selected terminal; Fig. 3 is a view in front elevation of a terminal bank showing the method of mounting the terminals and the relation of the brushes thereto when the device is used in connection with a three-wire circuit; Fig. 4 is a view in front elevation of a terminal bank illustrating a method of mounting the terminals and brushes for use of the device in a two-wire circuit; and Fig. 5 is a view showing part of the restoring mechanism of the device.

Referring to the drawings, and particularly to Fig. 1, 5 designates a rotatably and vertically movable shaft. Secured to said shaft is a ratchet wheel 6 adapted to be engaged by a pawl 7 controlled by an electromagnet 8 to rotate said shaft. Carried upon the shaft 5 above the ratchet wheel 6 is an escapement rack comprising teeth 10, adapted to coöperate with an escapement pawl 11 controlled by an electromagnet 12 to permit the step-by-step movement of said shaft 5 in a downward direction. Slidably mounted upon a second shaft 15, extending parallel to the shaft 5, are a plurality of brush carriages 16, 16. The brush carriages 16, 16 are adapted to move by gravity along the shaft 15, under control of the shaft 5, but are normally retained against such movement by means of a latch member 18, individual to each of said brush carriages. Mounted upon each of the carriages 16, 16 are brushes 20, 21, 22 and 23, adapted to coöperate with terminals in terminal banks in the manner hereinafter described. The brush carriages 16, 16, while slidable upon the shaft 15, are adapted to rotate through a

slight angle, in accordance with an angular displacement of the shaft 15. Preferably, the shaft 15 is made square in cross-section for this purpose. Means, either electromagnetic as shown in Fig. 1, or mechanical as shown in Fig. 2, are provided to displace the shaft 15 either to right or left for purposes of making contact between certain of the brushes and selected terminals in a bank, 10 as will be more fully explained hereinafter.

Assuming now that the switch is to operate in connection with a three-wire circuit, there will of course be three brushes and three terminals for each position of the 15 brush carriage away from normal. In Fig. 3, there is shown a scheme of mounting the terminals for a three-wire circuit. In this figure there are shown a plurality of terminals, 30, 30-31, 31-32, 32-33, 33-34, 20 34 and 35, 35. These terminals are mounted in pairs and in vertically arranged parallel rows in the bank, all of the terminals 30 and 31 being paired to form one row, 32 and 33 paired to form another row and the 25 terminals 34 and 35 paired to form a third row. The terminals 30 and 31, which are paired to form one row, have the separate terminals of each pair staggered with respect to each other in the direction of movement of the 30 brushes. The same relation exists between the separate terminals 32 and 33, and 34 and 35 of the other two rows. Also the pairs of terminals of each are in a staggered relation to the pairs in the other rows. That is, the 35 terminals 30 and 31, beginning at the top of the row, are higher in the bank than the first pair comprised of the terminals 32 and 33, which latter terminals are higher in the bank than the top pair 34 and 35 of the 40 third row. The terminals 31, 31 and 34, 34 of the two outside rows form the test terminals and are adapted to be wiped by the brushes 22 and 23 in the movement of the brush carriage 16. The brushes 22 and 23 45 are so mounted that they will not engage their respective terminals simultaneously. The terminals 30, 32, 33 and 35 may constitute the terminals of talking lines in a telephone exchange equipment, and in the structure shown the terminals 30 and 32 would be 50 in one circuit while 33 and 35 would be in another circuit.

The brushes 20 and 21 of the sets are mounted in a staggered relation to each 55 other, corresponding with the staggering of the pairs of contacts of adjacent rows of terminals and are adapted normally to pass between the rows of terminals without engagement therewith. These brushes 20 and 60 21 are adapted, however, as the shaft 15 is angularly displaced either to the left or the right, to engage terminals 30 and 32 or terminals 33 and 35 to close the corresponding circuits.

65 As shown in the drawings, the shaft 5 has

mounted upon it a plurality of pairs of radially extending arms 40, 41 and 40, 41, one for each brush carriage 16, the arm 40 being located directly above 41, and a plurality of sets of radially arranged arms 42, 70 43, 44, the number of these arms in a set corresponding to the number of contact banks in the switch to which a brush carriage 16 is common, the arms 42, 43, 44, etc., of each set being arranged spirally, back of the arms 75 41, 41, etc., of the same set.

Referring now to the operation of the device it will be assumed that the switch is to be operated to connect the brushes 20 and 21 of the uppermost brush carriage 16 80 with the fourth set of contacts in the first bank. The impulses for doing this will come over line wire 50, through an impulse relay 51 which, upon its first energization, completes a circuit for a slow-release relay 85 52, the armature of which remains attracted during the sending of a particular set of pulses. The first set of pulses will be for the purpose of operating the magnet 8 to rotate the shaft 5 into position, where the 90 uppermost arm 40 will be directly over an arm 53 on the latch 18 of the uppermost brush carriage 16. The current pulses for operating the magnet 8 will be from battery 54, through normal contact 55 of relay 51, alternate contact 56 of slow-release relay 52, switch arm 57, contact 58 and magnet 8 to ground. There will also be a branch circuit from battery 54, through a slow-release magnet 59 controlling an escapement 100 60 to which are attached switch arms 57 and 61. Upon the first energization of the magnet 8, the pawl 7 is brought into engagement with the ratchet wheel 6 to rotate the shaft 5 one step, and a contact 62 is closed 10 for completing a circuit through a slow-release magnet 63. The slow-release magnet 63, upon energization, releases a pawl 64 from a collar 65 on the lower end of the shaft 5, and draws a pawl 66 into position 11 to engage said collar without any downward movement of the shaft 5. The magnet 63, being slow to release, will hold the shaft in this position during the sending of the impulses through the magnet 8 for rotating 110 the shaft 5 into the desired position. As the pawl 7 moves inwardly on the first stepping impulse, a projection 67 thereon will engage one arm of a bell crank lever 68, to disengage the other arm thereof from a pivotal 120 holding pawl 69, which is caused to swing inwardly into engagement with the ratchet wheel 7, thereby holding the shaft 5 in its rotated position. When the stepping impulses over the line have ceased, the line 125 relay 51 will hold up, thus opening the circuit through the slow-release magnet 59 and also through the stepping magnet 8 at its normal contact 55. When magnet 59 releases its armature, the escapement 60 is 130

advanced one step, to advance the switch arms 57 and 61 from their first into their second positions. When the stepping impulses through the magnet 8 have ceased, 5 its armature will drop back, opening the contact 62 and thereby causing the deenergization of the magnet 63 to withdraw the pawl 66 and permit the shaft 5 to drop until the lowermost projection 10 of the escapement rack engages the pawl 11. This downward movement of the shaft 5 causes the arm 40 to engage the arm 53 of the latch 18, and releases the brush carriage 16, whereupon it will drop until the arm 53 strikes 10 and rests on the projecting arm 41 on the shaft 5 which is directly below the arm 40. The next step will be to rotate the shaft 5 until the arm opposite the bank containing the desired terminals is in position to catch 15 the brush carriage 16. In the case of the particular selection assumed, the terminals sought are in the first bank which is opposite the arm 42, and it will require one impulse to move the arm 42 into position to stop the 20 downward movement of the brush carriage 16 which will be released from the arm 41 by the second rotation of the shaft 5. The impulse for this will be over the line 50, as previously described, and the slow-release 25 magnet 59, operates the escapement 60 to move the switch arms 57 and 61 into their third position. In the third position of the switch arms 57 and 61, the arm 57 transfers the impulse circuit from the rotary magnet 30 8 to the vertical magnet 12, and since the brush carriage 16 is now resting on the arm 42, four impulses over the line circuit will operate the escapement 10-11 to drop 35 the shaft 5 and brush carriage 16 into position where the brushes 20 and 21 will be in 40 position to engage the fourth set of contacts in the first bank. As the shaft 5 moves downward, in response to the impulses through the magnet 12, a wiper 70 thereon 45 will wipe over contacts 71, 71, alternate ones of which are connected together to form a set, one of said sets being connected in circuit with a magnet 72, and the other of said sets being in circuit with a magnet 73, which 50 magnets are located adjacent the upper end of the shaft 15, and are adapted, when energized, to attract a common armature 74 to swing said shaft 15 to the right or to the left. At the end of the four impulses 55 left. At the end of the four impulses through the magnet 12, the sending circuit will again be interrupted at the sending station, and the magnet 59 again deenergizes to operate the escapement 60 to move the arms 57 and 61 into their fourth and final 60 position. In this position the switch arm 61 completes a circuit which may be traced from battery at 75, through switch arm 61, conductor 76, the wiper 70, the fourth one of the contacts 71, conductor 77 and magnet 65 72 to ground. The energization of the mag-

net 72 swings the shaft 15 to the right, looking at the face of the contact bank as in Fig. 3, and engages the brushes 20 and 21 with the fourth set of terminals in that bank.

So long as the line 50 is in use the line 70 relay 51 will remain energized, as will also the slow-release relay 52. As soon, however, as the line 50 is opened, relays 51 and 52 will drop off their armatures and thus close a circuit through a restoring magnet 75 80, which may be traced from battery at 54 through the normal contacts of relays 51 and 52, conductor 81, contacts 82 closed by the first downward movement of the shaft 5, and magnet 80. The energization of the 86 magnet 80 attracts its armature 83 to throw out holding and stepping pawls 84 and 85 of the escapement 59, thereby permitting it to return to normal under action of a spring (not shown). As the escapement 60 85 returns to normal, switch arm 61 opens the circuit through the magnet 72, thereby permitting shaft 15 to restore to its neutral position and disengage the brushes 20 and 21 from their contacts. The attraction of the 90 armature 83 of the magnet 80 releases a pawl 86, which permits a drum 87 to engage a clutch member 88 on a constantly rotating shaft 89, thereby to rotate the drum 87 and wind up a tape 90, carrying lugs 91 and 92. 95 The lug 91 engages an arm 93 on the shaft 5 to raise said shaft while the lug 92 engages with the arm of the latch 18 to restore the brush carriage 16 to normal or latching position. As the shaft 5 approaches its uppermost position, it opens the contacts 82, thereby breaking the circuit of magnet 80. At the same time a collar 95 on the shaft 5 engages the pawl 86 to move it into latching engagement with the armature 83. 100 There being no current through the magnet 63, the pawl 64 will engage the collar 65 to retain the shaft 5 in its normal vertical position. A collar 96 on the shaft 5 is adapted 105 when the said shaft 5 is moved upward to engage the holding pawl 69 and swing it away from the ratchet wheel 6 and into locking engagement with the bell crank lever 68. 110 As soon as holding pawl 69 is released from ratchet wheel 6, the shaft 5 will be rotated to normal position by means of spring 115 driven gear 97, which meshes with a feathered gear 98 on the upper end of the said shaft 5. Had the terminals to be selected been in 120 another of the banks to which the selected brush carriage is common, it would have been dropped into selective position with respect to this bank by bringing the corresponding arm 43, 44, 45 or 46, as the case 125 may be, into the path of movement of the arm 53. The selection of the terminals in the bank will then be accomplished by the downward movement of the shaft 5, as previously described. 130

In the modification shown in Fig. 2, the shaft 5 is provided with a notched rack 100 operating in conjunction with a swinging lever arm 101 to determine the direction in which the shaft 15 will be displaced. A pivotal T-shaped member 102, having one end in engagement with a pin 103, projecting from the shaft 15, is adapted to be engaged at its free ends by a pivotal operating member 104 operated upon the deenergization of a slow-release magnet 105, controlled over a circuit in parallel with the stepping magnet 12. During the stepping of the shaft 5 by the magnet 12, a pivotal arm 106 is lifted by the energization of the slow-release magnet 105 to hold the operating member 104 out of engagement with the T-shaped member 102. When, however, the stepping impulses cease, the arm 106 drops, and either the right-hand end or the left-hand end of the operating member 104 will engage the corresponding end of the T-shaped member 102, depending upon whether the lower end of the lever 101 is resting in a notch of the rack 100 or upon a high portion of the said rack between notches, thereby swinging the shaft 15 either to the right or the left.

When the switch is used with two-wire circuits and the test terminal is not required, the terminals and brushes may be arranged as shown in Fig. 4. In this view, the terminals of one circuit are shown mounted in pairs, one vertically above the other, and in two rows, the pairs of terminals in one row being staggered with respect to the pairs of terminals in the other row. The brushes are arranged to engage the terminals flatwise when the shaft is angularly displaced.

What is claimed is:

- 40 1. In a switching mechanism, a contact bank comprising a plurality of stationary contact terminals mounted in parallel rows, a movable contact arranged to be moved between the rows of said stationary terminals without engagement therewith until opposite a selected terminal, and means for then moving said movable contact into engagement with a selected terminal of either of the rows of the bank between which 50 said movable contact is arranged to be moved.
- 55 2. In a switching mechanism, a contact bank comprising a plurality of stationary contact terminals mounted in parallel rows, the terminals of one row being mounted in staggered relation with respect to the contacts of another row, a set of step-by-step movable contact members adapted to travel between the rows of stationary terminals 60 without engagement therewith, and means for swinging said movable contact members into engagement with selected ones of said stationary terminals.
- 65 3. In a switching mechanism, a bank of

contact terminals comprising a plurality of parallel vertical rows, the terminals in one row being vertically staggered with respect to the terminal of another row, movable brushes, means for moving said brushes step by step between the rows of terminals in 70 steps equal to the vertical distance between vertically adjacent terminals of adjacent rows without engagement therewith, and means for swinging said brushes into engagement with a selected set of said stationary terminals.

4. In a switching mechanism, a bank of contact terminals comprising a plurality of parallel vertical rows, the terminals in one row being vertically staggered with respect 80 to the terminals of another row, movably mounted brushes adapted to travel between the two rows of contacts without engagement therewith, step-by-step mechanism adapted to move said brushes in steps equal to the 85 vertical distance between vertically adjacent terminals of adjacent rows, means for swinging said brushes in either direction to engage selected terminals of a bank, and means controlled by said step-by-step mechanism 90 for determining the direction in which said brushes will be swung.

5. In a switching mechanism, a bank of contacts comprising a plurality of parallel vertical rows, two terminals in one row being vertically staggered with respect to the terminals of another row, movable brushes adapted to travel between the two rows of contacts without engagement therewith, a vertically movable shaft operated to move 100 said brushes in steps each equal to the vertical distance between vertically adjacent terminals of adjacent rows, means for angularly displacing said brushes to the right or left to bring them into engagement with selected terminals in the bank, and means controlled in the movement of said shaft to determine the direction in which said brushes will be displaced.

6. In a switching mechanism, a plurality 110 of banks each comprising a plurality of contact terminals, a set of brushes common to a plurality of said banks, a movable brush carriage for said brushes, a rotatable and vertically movable shaft, means controlled in the rotation of said shaft to select a brush carriage and cause it to move to a selected bank of terminals and by the vertical movement of said shaft to cause the movement of said brushes to engage a selected terminal in said bank.

7. In a switching mechanism, a plurality 115 of banks each comprising a plurality of contact terminals, a set of brushes common to a plurality of said banks, a movable brush carriage for said brushes, a rotatable and vertically movable shaft, means controlled 120 in the rotation of said shaft for selectively 125

releasing the brush carriage, means also controlled by the rotation of said shaft for controlling the vertical movement of said brush carriage step by step to a selected bank and 5 by the vertical movement of said shaft to cause the movement of the brushes into position to engage selected terminals in said bank.

8. In a switching mechanism, a plurality 10 of banks each comprising a plurality of contact terminals, a set of brushes common to a plurality of said banks, a gravity-operated brush carriage for said brushes, means for normally holding said brush carriage in 15 an elevated position, a rotatable and vertically movable shaft, means on said shaft adapted in the rotation thereof to be moved into position to trip said brush carriage, a plurality of spirally arranged arms on said 20 shaft adapted to be separately moved into the path of movement of said brush carriage to arrest its movement before a selected bank, and means for dropping said shaft step by 25 step to cause the selection of contact terminals in said bank.

9. In a telephone switching mechanism, a contact bank comprising a plurality of parallel rows of vertically arranged contacts, the contacts of each row being mounted in 30 pairs with the individual contacts of each row in staggered relation to each other and the pairs of contacts of one row being vertically staggered with respect to the contacts of the other row, the correspondingly staggered pairs in adjacent rows being connected with the same circuit, a plurality of movable brushes adapted to pass between the contacts of a plurality of rows without engagement therewith, and means for swing- 35

ing said brushes into engagement with corresponding contacts of adjacent rows. 40

10. In a telephone switching mechanism, a contact bank comprising three parallel rows of vertically arranged contacts, the contacts of each row being mounted in pairs 45 with the individual contacts of each row in staggered relation to each other, and the pairs of contacts of each row being vertically staggered with respect to the pairs of contacts of the other rows, the correspondingly staggered terminals of the pairs in adjacent rows being connected with the same circuit and the outside terminals of the outer rows being projected beyond the other terminals of the bank and adapted for test 50 purposes, a brush carriage, a pair of brushes thereon adapted to move between the middle and two outside rows of terminals without engagement therewith, a second pair of brushes adapted to engage the terminals of 55 the outside rows in the movement of said brush carriage, and means for swinging said first pair of brushes into engagement with corresponding contacts of adjacent rows.

11. In an automatic switch, a plurality of 60 contacts, a brush to coöperate with said contacts, a support, a plurality of stop members carried thereby, means for initiating the travel of said brush, and means operable during said travel for operating said support to position one of said stop members 65 to arrest the travel of said brush on a desired one of said contacts.

In witness whereof I hereunto subscribe my name this 15th day of August, A. D. 75 1916.

FRANK A. LUNDQUIST.
